GAS BURNER IGNITION DEVICE

Francis A. Wegener, Gloucester City, N. J., assignor to Welsbach Company, Gloucester City, N. J., a corporation of New Jersey

Application January 16, 1936, Serial No. 59,369

5 Claims. (Cl. 158—117.1)

The present invention relates broadly to the valved control of the flow of fluids. More particularly, it relates to the valved control of the flow of fluid fuel to burners such as gas burners.

In gas burners it is customary to provide a thermostatically operated safety shut-off which automatically shuts off the supply of gas to the burner should the burner flame become extinguished for any reason. In such burners it is customary to provide means for igniting the burner comprising manually operated, spring-closed, bypass valve means controlling a bypass flow around the main or burner valve which is shut off by the thermostat safety shut-off. This bypass flow, when ignited, serves to operate the thermostatic means controlling the burner valve, causing it to open that valve. When the burner valve has been opened sufficiently to provide a sufficient flow of gas therethrough to provide a self-maintaining flame at the burner ports, the bypass flow is terminated. This operation takes an appreciable interval of time, and the necessity of manually holding the bypass valve open for this period constitutes an annoyance to the user of the burner.

The principal object of the present invention is to provide apparatus in the use of which a bypass flow may be established around a closed valve and, without further attention by the operator, automatically terminated upon the opening of the said valve a predetermined distance.

Another object of the invention is to provide improved, valved, ignition apparatus for burners of the automatic thermostatic safety shut-off type embodying means for automatically maintaining the bypass flow to the burner for the period required by the thermostatic means to open the main burner valve sufficiently to establish a self-maintaining flame and for automatically shutting off the bypass flow thereafter.

Other objects of the invention will appear in connection with the description of the attached figures which form a part of this specification and which show a form of the invention chosen for illustration, and in which:

Figure 1 shows a cross-section of a gas burner, burner valve, thermostatic safety shut-off and ignition unit, with some parts shown in elevation.

Figure 2 shows an end view of a portion of the apparatus of Figure 1, with parts in cross-section.

Referring to the drawing, 1 generally indicates the burner valve casing provided with the chamber 3 on the gas inlet side of the main or burner valve 4 which seats on seat 5. The burner valve 4 establishes or cuts off communication between

the chamber 3 and the chamber 6 on the outlet side of the valve which is in open communication with the burner tube 7 which is provided with burner ports indicated at 8.

The burner valve is provided with the stem 9, 5 which terminates in or is attached to the adjusting screw 10 which is in threaded engagement with the end of the burner tube. 11 is a lock-nut for locking the adjusting screw 10.

The other end of the stem 9 fits loosely in a 10 recess 12 in the disc of the valve 4, abutting a washer 13 arranged in a spring chamber 14 in the valve body provided with the spring 15 which is seated against the valve body and the washer.

The valve disc is recessed at 16 to receive the 15 trigger cap member 17, which is in loose sliding engagement with the recess and in tight engagement with the trigger pin 18. The cap member 17 also forms a collar-bearing at 19, with the hollow lug 20 formed on the interior of valve casing and 20 extending within the chamber 3. The trigger pin 18 passes through the lug 20 and slides in the bushing 21 in valve casing 1. The cap member 17 also forms a seat for one end of the spring 22, the other end of which is seated against the interior 25 of the valve casing 1. The trigger cap and pin move as one piece and together may be termed the "trigger".

23 generally indicates the ignition valve unit which is attached to the valve casing 1 as, for instance, by screws such as 24 (shown in Fig. 2). Chamber 3 in the valve casing 1 is in open communication with the chamber 25 in the ignition valve unit 23 by way of passage 26 in the valve casing 1 and the ignition valve unit 23. Chamber 25 is provided with the spring-closed, flash lighter valve 27, which establishes or cuts off communication from the chamber 25, by way of passage 28 in the ignition valve unit and the valve casing 1, to the torch 29, which is adapted to direct a flame 40 to the burner ports 8.

In the apparatus illustrated, the valve 27 is manually operated by the push-button 30 to open the valve, and is provided with the spring 31 adapted to close the valve on the seat 32 when 45 pressure on the push-button is released.

The chamber 25 is also provided with the spring-closed valve 33, provided with seat 34 and spring 35 and adapted to establish or cut off communication between chamber 25 and the chamber 50 6, by way of passage 36 and annular passage 37 in the ignition valve unit and passage 38 in the burner valve casing 1, providing a bypass around the burner valve 4 when valve 33 is open.

Within the chamber 25 and positioned between 55

the valves 27 and 33, there is provided the notched latch-block 39, provided with notch 40. The block fits loosely within the chamber and is adapted to be moved longitudinally in the chamber by the valve 27 on the opening of that valve, thereby actuating valve 33 to open it against the pressure of the spring 35.

The latch-block 39 is pressed laterally against the end of the trigger 18 by the spring 41, so that on movement of the latch-block by the valve 27, when the burner valve 4 is closed, the notch 40 is adapted to engage the end of the trigger 18 which extends slightly beyond the face of the bushing 21 and into the chamber 25 in the closed position of the burner valve.

The passage 38 is provided with throttling means, as for instance the throttling screw 42, to adjust the quantity of gas bypassed around the burner valve 4 when the valve 33 is open. This screw may be covered as by the plug 43.

44 indicates an orifice plug with an orifice 45 of diameter chosen with regard to the gas rating of the burner for the duty required of it.

In operation, the adjusting screw 10 on the valve stem 9 is so adjusted that, when the burner tube 7 is cold and contracted in length, the burner valve 4 is tightly seated and the gas shut off from the burner, and, when the burner tube is hot and expanded in length by the heat of the combustion at the burner tube, the burner valve 4 is moved off the seat 5 to pass freely the gas flow permitted by the orifice 45.

The bushing 21 is set so that, when the burner tube is cold and the burner valve 4 is closed, the end of the trigger 17-18 projects slightly beyond the face of the bushing.

To ignite the burner, assuming gas has been turned on from the gas supply, the push-button 30 is pressed downward, opening the flash lighter valve 27 and moving the latch-block 39 longitudinally of the chamber 25, thereby opening the bypass valve 33.

As the chamber 25 is in open communication with the gas inlet 2 by way of chamber 3 in the valve casing and passage 26 in the valve casing and ignition valve unit, the opening of valve 27 admits gas to the torch 29 by way of passage 28, and the opening of valve 33 admits gas to burner port 8 by way of passage 36, annular passage 37, passage 38, chamber 6 in the valve casing and the burner tube 7.

The gas issuing from the torch 29 may be ignited by any convenient means, as by a match or by a constantly burning pilot flame. The resulting torch flame is projected to the burner ports, igniting the gas bypassed around the burner valve 4 by the opening of valve 33.

In the movement of the latch-block 39, as the block slides, the block is urged against the end of the trigger 21 by the spring 41. The notch 40, moving opposite to the slightly projecting end of the trigger, is engaged thereon by the lateral pressure of the spring 41, latching the block in this position and holding the valve 33 open, maintaining the bypass flow to the burner ports after pressure on the push-button 30 is released and the valve 27 closed by the spring 31, cutting off the gas flow to the torch 29 and extinguishing the torch flame.

70 The heat developed by the combustion of the bypass gas flow warms the burner tube, causing it to expand and lengthen. The pressure of the spring 22 causes the valve 4, stem 9, the trigger cap 17 and trigger pin 18, to follow the movement of the far end of the burner tube 7, the

trigger cap member 17 sliding on the lug 20, and the trigger pin 18 sliding within the bushing 21. The movement of the valve 4 opens the direct flow to the burner tube from chamber 3 through the valve 4-5 and chamber 6. When the valve has opened sufficiently, the movement of the trigger causes the trigger pin 18 no longer to project beyond the face of the bushing, withdrawing the end of the trigger from the notch 40 in the latch-block 39. This releases the valve 33, which is closed by the action of the spring 35, cutting off the bypass flow around the burner valve 4. The closure of the valve 33 moves the latch-block, so that the notch 40 is no longer opposite the end of the trigger pin 18.

Should the burner flames be extinguished for any reason, the cooling and consequent shortening of the burner tube moves the stem 9 inwardly toward the seat, reseating the burner valve 4. The stiff spring 15, interposed between the end of the stem and the valve body, releases the parts from undue strain which might be imposed by the shortening of the burner tube. The seating of the valve 4 moves the trigger so that it again extends slightly beyond the face of the bushing 21 and against the latch-block 39, so that the apparatus is automatically in position for the above-described ignition operation.

It will be seen from the above description that it is unnecessary to hold the flash lighter valve 30 and the bypass valve open manually until the combustion of the bypass heats the burner tube sufficiently to open the burner valve. It is only necessary to turn on the gas from the supply and momentarily press the button, igniting the torch with a match or pilot flame. The button may then be released and the maintenance of the bypass flow and its shut-off are automatically performed without further attention.

By adjusting the bushing 21, the length of the projection of the trigger pin 18 beyond the face of the bushing in the closed position of the burner valve may be changed to adjust the release of valve 33 and the cut-off of the bypass flow with respect to the degree of opening of the burner valve, so that the bypass flow is not cut off until the burner tube reaches a sufficiently high temperature to provide a self-maintaining flame by way of the open burner valve.

The trigger cap member 17 sliding on the lug 20 and the trigger pin 18 sliding in the bushing 21 form bearings to guide the movement of the burner valve 4, while the loose fit of the valve stem 9 and the trigger cap member 17 in the disc of valve 4 provides sufficient freedom to permit the valve to adjust itself on the seat 5.

I do not intend to be limited save as the scope of the prior art and of the attached claims may require.

I claim:

1. A gas burner ignition device comprising, a casing having an inlet and an outlet therein, a main valve controlling the supply of gas from said inlet to said outlet, a thermostatic device controlling said main valve and arranged to operate when heated by combustion of gas supplied to said outlet, a bypass conduit between said inlet and said outlet and bypassing said main valve, a bypass valve controlling said bypass conduit, a torch adapted to play a jet of flame to ignite gas passing from said outlet, a torch conduit leading from said inlet to said torch, a torch valve controlling said torch conduit, a latch block interposed between said torch valve and said bypass valve so that movement of said torch valve

to open position opens said bypass valve, and a latch controlled by said main valve for holding said latch block in position to hold said bypass valve open when said main valve is closed.

5. 2. A gas burner ignition device comprising, a casing having an inlet and a plurality of burner outlets therein, a main valve controlling the supply of gas from said inlet to said outlets, a spring stressing said valve toward open position, 10 a rod connected to a portion of said casing and to said main valve, whereby said valve can open upon expansion of said portion of said casing due to heat developed at said burner outlets when gas is burned at said outlets, a bypass conduit between 15 said inlet and said outlets and bypassing said main valve, a bypass valve controlling said bypass conduit, a torch adapted to play a jet of flame adjacent said outlets, a torch conduit leading from said inlet to said torch, a torch valve 20 controlling said torch conduit, a latch block interposed between said torch valve and said bypass valve so that movement of said torch valve to open position opens said bypass valve, and a latch controlled by said main valve for holding 25 said latch block in position to hold said bypass valve open when said main valve is closed.

3. A gas burner ignition device comprising, a hollow casing having a gas inlet therein, a hollow burner tube attached to said casing and having a 30 plurality of burner outlets therein, a main valve located in said casing between said inlet and said burner tube and controlling the supply of gas from said inlet to said outlets, a spring in said casing stressing said main valve to open 35 position, a rod adjustably secured at one end to said burner tube and pressing at its other end against said main valve, a bypass conduit leading from said inlet to said outlets and bypassing said main valve, a bypass valve controlling said bypass 40 conduit, a torch adapted to play a jet of flame adjacent said outlets, a torch conduit leading from said inlet to said torch, a torch valve controlling said torch conduit, a latch block interposed 45 between said torch valve and said bypass valve so that movement of said torch valve to

open position opens said bypass valve, and a latch controlled by said main valve for holding said latch block in position to hold said bypass valve open when said main valve is closed.

4. A valve casing providing a fluid way, a main valve in the fluid way, means to open and close the main valve, a by-pass conduit communicating with the fluid way on either side of the main valve, a by-pass valve in the conduit, means to open the by-pass valve, a trigger loosely fitting 10 in a recess in a face of the main valve and urged to follow the movement of the main valve by a spring member seated against said trigger and the valve casing, said trigger acting to automatically restrain the by-pass valve in open position 15 when opened with the main valve in closed position and for automatically releasing the by-pass valve upon movement of the main valve from its closed position, and means for automatically closing the by-pass valve upon such release. 20

5. A valve casing providing a fluid way, a main valve in the fluid way, means to open and close the main valve, a by-pass conduit communicating with the fluid way on either side of the main valve, a by-pass valve in the conduit, means to 25 open the by-pass valve, a trigger fitting loosely in a recess in a base of the main valve and urged to follow the movement of the valve by a spring member seated against said trigger and said valve 30 casing, said trigger provided with a trigger pin 35 arranged in sliding engagement with a bushing in said casing and extending there through and beyond the face of said bushing in the closed position of the main valve, said trigger serving to automatically restrain the by-pass valve in the 40 open position when opened with the main valve in closed position and for automatically releasing the by-pass valve upon movement of the main valve from its closed position, means for adjusting the projection of the end of said trigger pin 45 beyond the face of said bushing, and means for automatically closing the by-pass valve upon said release.

FRANCIS A. WEGENER. 45
